Primary Examiner — Patricia A Palasik(74) *Attorney, Agent, or Firm* — Sutton Magidoff
 Barkume LLP(57) **CLAIM**

The ornamental design for a robotic arm, as shown and described.

DESCRIPTION

FIG. 1 is a back view of the upper joint of a robotic arm showing our new design;

FIG. 2 is a front view thereof;

FIG. 3 is a rear left perspective view thereof;

FIG. 4 is a right view thereof;

FIG. 5 is a left view thereof;

FIG. 6 is a front left perspective view thereof;

FIG. 7 is a perspective view thereof in context;

FIG. 8 is a bottom view thereof; and,

FIG. 9 is a top view thereof.

The portions of the robotic arm, shown overexposed in FIG. 15 is for the purpose of illustrating environment that forms no part of the claimed design.

1 Claim, 8 Drawing Sheets(56)
